United States Patent Office.

ISRAEL L. LANDIS, OF LANCASTER, PENNSYLVANIA.

Letters Patent No. 64,835, dated April 30, 1867

IMPROVEMENT IN PORTABLE FENCES.

The Schedule referred to in these Letters Patent and making part of the same.

TO ALL WHOM IT MAY CONCERN:

Be it known that I, ISRAEL L. LANDIS, of Lancaster city, county of Lancaster, and State of Pennsylvania, have invented a new and improved Portable Fence; and I do hereby declare the following to be an exact description thereof, reference being had to the accompanying drawings, and to the letters of reference marked thereon, making a part of this specification.

The nature of my invention consists in the construction of a notch brace, (with pins,) fitting into notches in the posts to suit either a rail or pale fence, in combination with the mode of fastening the rails by pins, so that the fence can be easily taken apart for transportation or laying aside.

Figure 1 represents a view of the fence as connected at the ends of the panels, either a rail or pale fence.

Figure 2 shows the shape and construction of the notched brace and pins.

Figure 3 shows the notches in the posts in which the braces fit and bind the posts.

A represents the rails or panels; B, the pins that connect them; C, the posts; D, the notches in the posts; E, the notched-brace or clamp, with the square notch F in the side, at the centre, with apertures at the ends through which pins G are passed to lock against the outside of the rails. The pins G are long, and made the whole length of a pale when a pale fence is to be connected by the braces E.

What I claim as my invention, and desire to secure by Letters Patent, is—

The construction of the notched brace E, with its pins G, or rod G, when combined and used with a rail or pale fence, fastened together with pins B, as herein described and for the purposes set forth.

ISRAEL L. LANDIS.
